UNITED STATES PATENT OFFICE.

WILLIAM GRABER, OF BROOKLYN, NEW YORK.

SKIRT.

1,333,410.

Specification of Letters Patent.

Patented Mar. 9, 1920.

Application filed July 29, 1919. Serial No. 314,022.

To all whom it may concern:

Be it known that I, WILLIAM GRABER, a citizen of the United States, residing at the city of New York, in the borough of Brooklyn and State of New York, have invented 5 certain new and useful Improvements in Skirts, of which the following is a full, clear, and exact description.

This invention relates to skirts for women's wear, the object being to provide 10 an appliance and structure for a skirt, by means of which the waist band may be readily adjusted to various sizes within a wide range without affecting the fit or appearance 15 of the skirt. Such a skirt becomes useful as a garment for ordinary wear, as a sport skirt, as a maternity skirt, or for any purpose where a change in size is desired or required.

20 The improved skirt is provided with a waist band, a section of which, preferably at the front, is of permanent or unalterable size, while the remainder of the band is adjustable in length to effect a change of size 25 of the band as a whole. This adjustable portion of the band is composed of a tubular pocket through which a rigid band passes, one end of the band being secured to the 30 skirt adjacent to one extremity of the front section and extending freely through the tubular portion of the skirt, projecting therefrom at a point adjacent to the opposite end 35 of the front section and adapted to overlap said front section to any desired extent and be secured thereto at any point of adjustment, the said tubular portion of the skirt being evenly distributed along such portion 40 of the rigid band as extends between the two terminals of the unaltered front section.

45 The invention will be described in detail in connection with the accompanying drawing, in which the figure is a perspective view of the upper portion of a skirt, taken from the rear and embodying the improvements.

50 The upper edge or waist band of the skirt is provided with a tubular pocket or hem *a* which extends from a point *b* at one side of the front, around the sides and back, to a point *c*, and encompassing approximately 55 three-quarters of the entire waist band. Passing freely through this tubular pocket 60 is a belt, band or cord *d*, one end of which is permanently fastened by stitching or otherwise to the skirt at the point *b* where it enters the pocket, while the other end of the band passes freely out through the other ex-

65 tremity *c* of the pocket and is adapted to overlie, to any desired extent, that portion of the waist band of the skirt at the front along which the pocket does not extend. 60 The fixed end of the belt *d* preferably extends from the point *b* where it enters the pocket, in the opposite direction, along the inside of the front section of the waist band to which it is permanently fastened by 65 stitching *e*. To this portion of the belt or to the waist band at this location are attached a plurality of fastening devices *f*, while the free end of the band is provided with corresponding fasteners adapted to coöperate 70 with those on the fixed end of the belt to secure the two ends of the belt together at any size of waist determined by the amount which the free end of the belt overlaps the 75 fixed end. At one side of the front panel of the skirt is a placket *g* which may be opened when the ends of the belt are disconnected, to facilitate applying the garment to the body and removing it therefrom. When the free end of the belt overlaps the full length 80 of the front section of the skirt, that is to say, when it extends substantially to the point *b*, the waist is at the smallest possible size; conversely when the free end of the belt overlaps the front section to the slightest extent, the waist line is of the largest possible 85 size. Under either of these conditions, or when the overlapping belt is at any intermediate position, the position of the placket remains the same and the appearance of the front section or panel of the skirt is not affected. But when the waist is at its smallest 90 size, the hem or pocket must be gathered or shirred and evenly distributed upon the belt. Likewise when the size is increased, the shirring must be flattened out and again distributed evenly between the points *b* and *c*. Since the front panel of the skirt is not affected by a change made in the size of the 95 waist, and since it is possible to evenly distribute the side and rear portions of the skirt to compensate for any adjustment of the size, it is evident that a change in size will not affect the appearance or the fit of the skirt. The fastening devices herein referred 100 to are of the well known character and may be substituted by others of different kind.

I claim:

1. A skirt provided with a tubular pocket 110 extending part way around the waist, in combination with a band passing freely through said pocket and having one end

fastened at a point adjacent one end of the pocket and the other end free and projecting beyond the other end of the pocket.

2. A skirt provided with a tubular pocket extending part way around the waist, in combination with a band passing freely through said pocket and having one end fastened at a point adjacent one end of the pocket and the other end free and project-

ing beyond the other end of the pocket, and 10 coöperating fastening devices located on the free end of the band and on that part of the waist band between the extremities of the pocket.

In witness whereof I subscribe my signature.

WILLIAM GRABER.
